UNITED STATES PATENT OFFICE

147,995

DESIGN FOR A SLIPPER

Myer S. Silver, Brookline, Mass.

Application May 21, 1947, Serial No. 139,187

Term of patent 7 years

(Cl. D7—7)

To all whom it may concern:

Be it known that I, Myer S. Silver, a citizen of the United States, residing at Brookline, in the county of Norfolk and Commonwealth of Massachusetts, have invented a new, original, and ornamental Design for Slipper, of which the following is a specification, reference being had to the accompanying drawing, forming part thereof.

In the drawings:

Fig. 1 is a side elevational view of a slipper showing my new design with the tops of the vamp and quarter portions in an upright position, the opposite side presenting substantially the same appearance as the side shown; and

Fig. 2 is a side elevational view of the slipper shown in Fig. 1 but showing the tops of the vamp and quarter portions folded downwardly and outwardly.

I claim:

The ornamental design for a slipper, substantially as shown and described.

MYER S. SILVER.
